UNITED STATES PATENT OFFICE

HEZEKIAH W. CARROLL, JR., OF HOBOKEN, NEW JERSEY, ASSIGNOR TO AUTOGRAPHIC REGISTER CO., OF HOBOKEN, NEW JERSEY, A CORPORATION OF NEW JERSEY

MANIFOLDING REGISTER

Application filed March 6, 1926. Serial No. 92,784.

This invention relates to manifolding machines and more particularly to improved means for receiving and storing the worksheets which are to be retained in the machine.

Heretofore, it has been proposed to cut from a continuous strip and store one of the copies or forms of worksheets written in the machine so that the accumulation of such forms will be held upon rods or posts to form a collated pack. In each of said proposals, however, it was necessary to impale the forms by the lower or foot-ends of the forms.

Now, it is the practice to provide the forms with apertures at their upper or head ends which apertures are utilized to control the feeding of forms, and to receive the posts of loose-leaf binders etc., after the sheets have been taken from the machine.

According to this invention, these pre-existing apertures are utilized in collating the stored forms upon pins or posts so that no new holes need be made at the foot-ends of the forms and so that the collated pack of sheets will be, as they ultimately are now arranged by hand operations, properly impaled upon posts or pins by their upper or head-ends.

Another object of this invention is to provide means whereby the forms may be collated directly on the pins or posts of a loose-leaf binder, so that the binder, with its posts and the collated forms, may be removed from the machine en bloc, thus saving the operator of the machine the time and trouble of transferring the forms to a binder.

A further object is to so guide the forms in the storage compartment as to prevent the forms from somersaulting or folding over or otherwise becoming disarranged therein.

And a still further object is to move the form guiding and controlling means to such positions at the time the storage compartment is opened that they will not interfere with the removal of the pack of stored forms.

Other objects and advantages will herein-after appear.

In the accompanying drawings, which illustrate one form of the invention, that at present preferred—

Figure 1 is a top plan showing a manifold-

ing machine with the cover of the storage compartment in its open position.

Fig. 2 is a side view of the machine shown in Fig. 1, with parts of the casing removed to show parts of the mechanism.

Fig. 3 is a fragmentary view of part of the register, showing the disappearing platform or table in its inoperative position.

Fig. 4 is a side sectional view of the delivery side of the machine shown in Fig. 1.

As shown in the accompanying drawings, the manifolding machine to which the present invention is preferably applied, comprises side frames 10 suitably tied together and provided with a bottom 11, a top 12 beneath an opening 13 of which there is located a writing bed or platen 14; and a compartment 15 for receiving and storing until used a supply of worksheets 16 of indefinite length, which worksheets are fed over guide rollers 17 to the platen 14 where they are interposed with carbon paper and from which positions they are led to feed mechanism comprising one or more feed rollers 18 and one or more pressure rollers 19.

When the feed-rollers 18 and pressure rollers 19 are rotated, the worksheets 16 are drawn from the supply compartment 15 over the guide rollers 17 across the platen; and those which are to be issued from the machine are fed through a delivery opening 20 under a knife bar 21 (see Fig. 4), against which the delivered forms may be torn from those immediately following them and which are then in writing positions. Of course, as many worksheets 16 as are desired may be issued from the machine in the above manner and may then be distributed according to the system employed by the user of the machine.

In the type of manifolding machine above described, the feed rollers 18 and pressure rollers 19 are driven by the oscillatory movement of a handle 22 connected to the feed rollers 18 by means of gearing 23 located in a gear house 24. The handle is normally located in the position shown in Fig. 2, and when pulled rearwardly (toward the right as seen in Fig. 2) the feed rollers are driven to issue the forms from the machine. When the handle is released and returned to normal position, the

feed rollers are not driven because of a one-way driving connection in the train of gearing 22.

Also, in the type of manifolding machine being described, there is provided means for storing in the register one copy of each form written. This means comprises a guide 28 located near the feed rollers 18 and pressure rollers 19 and adapted to guide the form to be retained downwardly while the forms to be issued are guided upwardly to the delivery opening 20. The record storing means also comprises a compartment 29 provided at the delivery side of the machine into which the written forms to be stored may fall, to be there held until desired, after they are severed one by one from the continuous strip to which they are attached by the operation of a severing device 30. This severing device 30 comprises a pair of grippers 31 for holding the strip of paper at each side of the severing point and a knife or cutter 32 which enters an opening in the guide 28 when operated to sever the form to be stored from the remainder of the strip to which it is attached. The knife 32 and grippers 31 are mounted in a reciprocable frame 33 carried by rocker arms 34 secured to the shaft 27, so that, when the shaft 27 is rocked, the frame 33 will be moved upwardly to first cause the grippers to engage the strip and then cause the knife to pierce the strip between the points where it is held by the grippers, the grippers being held spring-pressed against the deflector 28 during the severing movement of the knife by springs 35 located between the reciprocable frame 33 and the grippers 31.

The upper ends of the springs 35 are connected to ears on the frame 33 and the lower ends are connected to the plates carrying the grippers 31, so that when the frame 33 is raised the grippers first engage the strip to hold it and then, further upward movement of the grippers being prevented, the springs 35 stretch and allow the knife to pierce the strip.

This severing operation of the record form is performed by properly timing the operation of the parts after the feeding operation of the forms has been concluded and as the handle 23 approaches the rearward limit of its movement, which limit is defined by a stop 36 secured to the side frame 11 of the register and adapted to be struck by the handle. During the rearward movement of the handle 23 the knife 32 is withdrawn to idle or inoperative position and then the grippers 31 are withdrawn from engagement with the strip so that the severed form is free to drop to its resting place in the record compartment 29. A door or cover 37 is provided on the record compartment 29 so that, when desired, the stored forms may be removed from the record compartment.

The type of feed mechanism employed to feed the forms in the register being described in preferably that embodying the principles disclosed in the Shoup and Oliver Patent #1,396,070, dated November 8th, 1921. In this type of feeding mechanism the worksheets or forms are fed until apertures provided in the forms, usually at the head end of the forms, reach the bight of the feed rollers 18 which are preferably in the form of annuli, whereupon the feeding operation ceases because of lack of contact of the feed rollers with the forms.

The manifolding register, so far as above described, is that now manufactured and sold by the Autographic Register Company, of Hoboken, New Jersey, to which machine reference may be had if a more complete understanding of the mechanism described is desired.

Now, according to the present invention, the forms which are stored in the compartments 29 are not merely allowed to fall in the compartments to take whatever positions they may, but are so controlled and guided that they are collated in a pack upon suitable pins which pass through the apertures A in the head-ends of the form.

Accordingly, there is fixed to each side wall 10 of the machine in the compartment 29, a pair of brackets 38 which pivotally support a rod or shaft 39 carrying arms 40 on which there is secured a leaf or table 41 extending from a position close to the side wall 10 toward the center of the machine where it terminates in close proximity to pins or posts 42 upon which the stored forms are to be collated. The shelves or tables 41 are so positioned in the compartment 29 that when the head-end of a form to be stored passes from under the guide bar 28 when the forms are being fed, it will drop upon the tables or shelves 41 and will thus be prevented from immediately falling in the compartment 29, for the shelves 41 are held in elevated position by springs 43 surrounding the shaft 39, during the feeding operations of the worksheets.

In order to insure that the form moves in a straight line on the tables 41 without deviating to either one side or the other and so as to properly locate the forms laterally of the machine, there is provided a pair of lateral guides 43^a extending substantially the full length of the tables or shelves 41 and passing below the level of the shelves when the latter are in their guiding positions so that no openings are permitted between the shelves and the guides which would allow passage of the edges of the sheets therethrough. Hence, when the form is fed onto the tables 41, its lateral position is accurately determined by the lateral guides 43, and at the conclusion of the feeding operation

it will be located in proper position to be received on the collating pins 42.

These collating pins 42 are located near the front of the machine and extend vertically upward from a platform or table 44 at the bottom of the machine. The pins 42 may be secured directly to the platform 40, or, in order to facilitate the use of the machine, they may be mounted directly in a loose-leaf book binder 45 which is suitably located and positioned on the table 44 by side and end guides 46.

The parts above described might be so arranged that when the feeding movement of the record form is concluded, the apertures A of the form would extend over the pins 42 so that when the tables 41 are allowed to descend the forms would naturally fall on the pins.

However, it will be noted from Fig. 4, that at that time the entire record form is not supported by the tables 41, but that the foot-end thereof is held elevated by engagement with the gripper 31 which prevents the direct descent of the form even when returned to normal position out of engagement with the form. Hence, the form must be drawn forwardly if it is to be allowed to fall without interference with the gripper.

To do this, and to more positively insure that the form will be impaled on the pins 42, the pins are made to extend slightly above the level of the form when resting on the tables 41, and the pins are mounted to move rearwardly and forwardly at the proper time to first engage themselves in the apertures A and then draw the form forwardly out of range of the gripper 31. For this purpose, the platform 44, carrying the pins 42, is mounted to slide on guides 47 and is moved rearwardly to position to cause the pins 42 to engage the apertures A by a link 48 having a pin-and-slot connection 49 with an arm 50 secured to the platform 44. The link 48 is carried by an arm 51 secured to the shaft 27 operated by the crank 23. When the crank 23 reaches the end of its rearward movement and the feeding of the forms has ceased, the shaft 27 is rocked to operate the knife frame 33 and at the same time the platform 44 and the pins 42 are drawn rearwardly causing the pins to enter the apertures A in the record form. Then, as the crank 23 is returned to its normal forward position, the link 48 moves forwardly away from the arm 50 on the platform and a spring 52 connected between the platform and its guides 47 causes the platform to move forwardly so that the pins 42, then in engagement with

the form, draw the form forwardly away from the gripper 31 and related parts, the parts moving to the positions shown in dot-and-dash lines in Fig. 4.

When the record form thus rests on the table 41 the latter may be made to collapse

so that the form may drop on the pile of those which preceded it. The preferred means for this purpose, as illustrated in the accompanying drawings, comprises a plunger 52 mounted to slide in a bracket 53 carried by the side 10 of the register, the plunger being in position to be struck by a bumper 54 on the crank 23 when the crank returns to its normal position and to be permitted to move when the crank 23 leaves its normal position. This plunger 52 is connected by a pin-and-slot connection 55 to an arm 56 pivoted at 57^a on the side 10 which arm 56 is connected by a link 57 to an arm 58 on a rock-shaft 59 mounted in the sides 10 and located across the register near the front wall thereof. The rock-shaft 59 also has a pair of arms 60 secured thereto which carry a bail 61 comprising arms 62 and transverse rod 63. The arrangement is such that when the arm 56 is rocked the bail 61 moves up-and-down. This up-and-down movement of the bail 61 controls the tables 41 since the shaft 39 of each table 41 has an arm 64 secured thereon having a roller 65 resting under the rod 63 of the bail.

Thus, when the bail is moved up by the action of a spring 66 when the crank 23 leaves its normal position in starting to feed the forms, the tables 41 by the action of their own springs 43 swing up to position shown in Fig. 4 to receive the record form, and when the crank 23 returns to its normal position the bail is pulled down by the weight of the crank and the tables 41 are collapsed to allow the record form to fall on the pile.

In order to insure that the forms properly engage the pins, a pair of pressure fingers 67 are provided in close proximity to the pins. These fingers are hinged on a rod 68 extending across the register between the lateral guides 43^a, and urge the form downwardly in the vicinity of the pins 42 merely by their own weight. To prevent the leading edge of the advancing record form from catching on the rod 68, a deflector 69 is secured to the cover 37 to extend from the cover to a position below the rod 68.

In order to prevent overthrow of the record form when it is drawn forwardly on the tables 41 from under the grippers 31 by the pins 42, there is provided a leading edge gage 70 secured to the cover 37 and extending to a position below the tables 41. Hence, it will be struck by leading edge of the form should the latter attempt to move so far that there would be danger of the apertures A becoming disengaged from the pins 42.

It will be noted that the lateral guides 43^a, the pressure fingers 67 and deflector 69 and the leading edge gage are all mounted in the cover. Hence, when it is desired to inspect the compartment 29 or remove therefrom any or all the forms, the necessary operation of

raising the cover to gain access to the compartment will at the same time move the above named parts out of the way.

Moreover, since the register is usually inspected only when the crank is in its normal position, and since in this position the tables 41 are collapsed, the latter in no way interferes with the removal of the pile of record forms from the register when desired.

10 Variations and modifications may be made within the scope of this invention, and portions of the improvements may be used without others.

Having now described the invention, what 15 is claimed as new and for which it is desired to obtain Letters Patent, is:—

1. In a manifolding device, record-storage means comprising collating pins; means for guiding forms, having apertures at their head-ends, to a position to be received and stored face upward upon said collating pins; means for moving said pins into said apertures; and means for holding the forms against movement while said pins are moving into said apertures.

2. In a manifolding device, record-storage means comprising collating pins; horizontally disposed tables for guiding forms, having apertures at their head-ends, to a position to be received upon said collating pins; and lateral guides for engaging the side edges of said forms during movement thereof on the tables.

3. In a manifolding device, record-storage means comprising collating pins; horizontal tables for guiding forms, having apertures at their head-ends, to a position to be received upon said collating pins; a supporting device for said collating pins; and means for shifting said supporting device to move the collating pins into said apertures.

4. In a manifolding device, record-storage means comprising collating pins; horizontal tables for guiding forms, having apertures at their head-ends, to a position to be received upon said collating pins; means for moving said collating pins into said apertures; and means bearing upon said forms in the vicinity of said collating pins for backing-up the forms while the pins move into the apertures.

5. In a manifolding device, record-storage means comprising collating pins; means for guiding forms, having apertures at their head-ends, to a position to be received upon said collating pins; supporting means for said collating pins; and positively acting means for shifting said supporting means to cause the pins to enter apertures in said forms.

6. In a manifolding device, web feeding means including a handle; record-storage means comprising collating pins; horizontal tables for guiding forms, having apertures at their head-ends, to a position to be re-

ceived upon said collating pins; and means operated by the web feeding means for automatically rendering said horizontal tables inoperative.

7. In a manifolding machine, worksheet guiding means; worksheet severing means; a worksheet storage compartment; and a flanged tray in said compartment for supporting snugly within the tray a loose-leaf binder in position to receive worksheets, as they are fed and severed, upon worksheet engaging means forming part of said loose-leaf binder.

8. In a manifolding register, a storage compartment; and means in said storage compartment for removably supporting therein a loose-leaf binder, said means having lateral and end guides for holding the binder in desired position on the said means.

9. A manifolding machine comprising a worksheet storing compartment; movable closure means for the compartment; and lateral guiding means and worksheet engaging fingers mounted on said movable closure means so that said lateral guides and worksheet engaging fingers are removed from the compartment when said closure means is moved to open the compartment.

10. A manifolding device, worksheet feeding means; a storage compartment into which said worksheets are fed to there fall one upon another to form a pack; means for delaying the falling of the said worksheets; and means operated automatically after the completion of the feeding operation for moving said delaying means to inoperative position.

11. In a manifolding device, worksheet feeding means; a storage compartment into which said worksheets are fed to there fall one upon another to form a pack; means for delaying the falling of the said worksheets during the feeding operation; and means operated by the feeding means for moving the said delaying means automatically to inoperative position after the completion of the feeding operation.

12. In a manifolding device, worksheet feeding means comprising a reciprocable handle; a storage compartment into which said worksheets are fed to there fall one upon another to form a pack; means for delaying the falling of the said worksheets until a predetermined time; and means actuated by said handle for making said delaying means operative and inoperative.

13. In a manifolding device, worksheet feeding means comprising a handle having a normal starting position; a storage compartment into which worksheets are fed to there fall one upon another to form a pack; means for delaying the falling of the fed worksheets until a predetermined time; and means made operative when the handle is returned to its starting position for rendering said delaying means inoperative.

14. In a manifolding device, worksheet feeding means; a storage compartment into which said worksheets are fed to there fall one upon another to form a pack; and means for delaying the falling of the fed worksheets until a predetermined time, said means being in ineffective position when the feeding means of the machine is not in use.
15. In a manifolding device, worksheet feeding means including a reciprocable handle; a storage compartment to which said worksheets are fed to there fall one upon another to form a pack; means for delaying the falling of the fed worksheets; and means rendered operative as an incident to the returning movement of the handle for rendering said delaying means inoperative.
16. In a manifolding device, worksheet feeding means comprising a handle; a storage compartment into which said worksheets are fed to there fall one upon another to form a pack; hinged shelves in said storage compartment for delaying the falling of the fed worksheets until a predetermined time; and means operated by the handle for making the shelves inoperative.
17. In a manifolding device, worksheet feeding means comprising a handle; a storage compartment into which said worksheets are fed to there fall one upon another to form a pack; a trap platform for delaying the falling of the fed worksheets; and means operated by said handle for rendering said trap platform inoperative.
18. In a manifolding device, means for feeding a worksheet form lengths; means for severing the form fed from the form to be fed; means adjacent the severing means for clamping the worksheet against movement during the severing operation of the severing means; and means for positively pulling the severed form away from the clamping means when the clamping means releases its clamping action on the severed form.
19. In a manfolding device, means for feeding a worksheet form lengths; means for severing the form fed from the form to be fed; collating pins adapted to extend into apertures in the fed form but out of range of said apertures at the end of the feeding operation; means common to the severing means and the collating pins adapted to cause the worksheet to be severed and the pins to move into range of the apertures in the fed form simultaneously; and means for clamping the severed form during movement of the pins into range of the apertures.

Signed at Hoboken, in the county of Hudson, and State of New Jersey, this 3rd day of March, 1926.

HEZEKIAH W. CARROLL, JR.
